TAP HANDLE OR SIMILAR ARTICLE

Opal L. Stewart, North Attleboro, Mass., and Donald M. Slipp, East Greenwich, R.I., assignors to Clearfloat, Inc., Attleboro, Mass., a corporation of Massachusetts

Filed Mar. 11, 1963, Ser. No. 73,902

Term of patent 14 years

(Cl. D2—3)

FIG. 1

FIG. 2

FIG. 3

FIG. 5

The dominant features of our design reside in the portions shown in full lines.

We claim:

The ornamental design for a tap handle or similar article, as shown and described.
